UNITED STATES PATENT OFFICE.

CHAUNCEY MARSH GOODRICH, OF WINDSOR, ONTARIO, CANADA.

ELECTRIFICATION POLE.

Application filed February 7, 1925, Serial No. 7,582, and in Canada December 9, 1924.

This invention relates to supports for wires, cables or other electric current conductors, and more particularly to towers or poles for carrying the overhead catenary construction of electrified railways and the like, and has for its object the provision of towers or poles of this class that are so designed that they will carry stresses from the point of support to the pole in a plurality of planes.

Another object is to provide a pole having the novel construction, arrangement and combination of parts hereinafter described and illustrated in the accompanying drawings.

In the drawings:

Figure 1 is a side elevation of an electrification pole fitted with my improved load carrying arm.

Figure 2 is a front elevation.

Figure 3 is a top plan view of the load carrying arm showing the wooden block.

Figure 4 is a top plan view of an arm for carrying telephone wires.

Figure 5 is a plan view of the lower flange of the arm.

Figure 6 is a perspective detail of the adjusting means for the pole to raise it or lower it.

Referring now more particularly to the drawings, the numeral 10 designates the pole comprising a skeleton structure having four vertically extending posts 11. This pole is of well-known construction and provided with the brace members 13. At its lower end it is designed to be set in the ground encased in a concrete foundation 15.

As illustrated in the accompanying drawings, the pole is formed in two sections 16 and 17 adapted, as illustrated in Figure 5, to slidably engage with one another. The lower section 17 is provided with a plurality of apertures 18, which are in turn adapted to register with apertures 19 in the upper section 16 whereby the upper section is raised or lowered, the apertures being designed to receive therethrough suitable securing means.

Coming now to the essential feature of my invention, this consists in the combination with a suitable pole or tower construction, of a cantilever arm 20 composed of a pair of horizontally spaced upper chord members 21 rigidly secured to the pole at their inner ends, as at 26, and converging towards their

outer ends, and a pair of horizontally spaced lower chord members 22 rigidly secured to the pole at their inner ends, as at 25, and converging towards a point at their outer ends beyond the point towards which said upper chord members converge. A series of lacing members 28 extend between and connect said upper and lower chord members so as to form, in effect, two substantially vertical trusses, one of which forms each side of said arm. A block 30, preferably composed of impregnated wood or other insulating material, is rigidly secured between said substantially vertical trusses formed by lacing said upper and lower chord members. The block 30 is secured to said trusses at the outer end and at least one panel point by bolts 29, so that loads and torsions delivered to said block in any direction and in any plane will be carried by said arm to said tower as axial stresses in the members composing said arm.

The insulating block 30 is provided with the usual insulators 31 to support the usual messenger cables or other support of the overhead construction of electric railways.

From the above it will be readily appreciated that the main feature of my invention is the support of the insulating block in such a manner that a vertical load may be imposed upon it at any point without causing other than axial stresses in the members forming the arm 20. Another feature of my invention is the support of the insulating block in such a manner that a horizontal or other inclined or non-vertical load may be applied to it at any point without causing other than axial stresses in the members forming the arm.

While I have shown and described only one specific embodiment of my invention, it will be understood that I do not wish to be limited thereto, since various modifications may be made without departing from the scope of my invention as defined in the appended claim.

I claim:

In a device of the character described and in combination, a pole, a cantilever arm supported on said pole, said arm comprising a pair of horizontally spaced upper chord members rigidly secured to the pole at their inner ends and converging towards their outer ends, a pair of horizontally spaced lower chord members rigidly secured to the

pole at their inner ends and converging towards a point at their outer ends beyond the point towards which said upper chord members converge, a series of lacing members extending between and connecting said upper and lower chord members forming two substantially vertical trusses, a block rigidly secured between said substantially vertical trusses at the outer end and at least

one panel point of said trusses, so that loads 10 and torsions delivered to said block in any direction and in any plane will be carried by said arm to said pole as axial stresses in the members composing said arm.

In testimony whereof I have hereunto signed my name.

CHAUNCEY MARSH GOODRICH.
